CLAIM

The ornamental design for a foldable mat, as shown and described.

DESCRIPTION

FIG. 1 is a perspective view of a foldable mat in accordance with a first embodiment of the invention;

FIG. 2 is a front elevational view of the foldable mat of FIG. 1, the rear elevational view being a mirror image of the front;

FIG. 3 is a right side elevational view of the foldable mat of FIG. 1;

FIG. 4 is a left side elevational view of the foldable mat of FIG. 1;

FIG. 5 is a top plan view of the foldable mat of FIG. 1, the bottom plan view being a mirror image of the top;

FIG. 6 is a perspective view of the foldable mat of FIG. 1 shown in a partially folded orientation;

FIG. 7 is a front elevational view of the foldable mat as shown in FIG. 6, the rear elevational view being a mirror image of the front;

FIG. 8 is a right side elevational view of the foldable mat as shown in FIG. 6;

FIG. 9 is a left side elevational view of the foldable mat as shown in FIG. 6;

FIG. 10 is a top plan view of the foldable mat as shown in FIG. 6, the bottom plan view being a mirror image of the top;

FIG. 11 is a perspective view of the foldable mat of FIG. 1 in a folded orientation;

FIG. 12 is a front elevational view of the foldable mat as shown in FIG. 11, the rear elevational view being a mirror image of the front;

FIG. 13 is a right side elevational view of the foldable mat as shown in FIG. 11;

FIG. 14 is a left side elevational view of the foldable mat as shown in FIG. 11;

FIG. 15 is a top plan view of the foldable mat as shown in FIG. 11;

FIG. 16 is a bottom plan view of the foldable mat as shown in FIG. 11;

FIG. 17 is a perspective view of a foldable mat in accordance with a second embodiment of the design;

FIG. 18 is a front elevational view of the foldable mat of FIG. 17, the rear elevational view being a mirror image of the front;

FIG. 19 is a right side elevational view of the foldable mat of FIG. 17;

FIG. 20 is a left side elevational view of the foldable mat of FIG. 17;

FIG. 21 is a top plan view of the foldable mat of FIG. 17;

FIG. 22 is a bottom plan view of the foldable mat of FIG. 17;

FIG. 23 is a perspective view of the foldable mat of FIG. 17 shown in a partially folded orientation;

FIG. 24 is a front elevational view of the foldable mat as shown in FIG. 23, the rear elevational view being a mirror image of the front;

FIG. 25 is a right side elevational view of the foldable mat as shown in FIG. 23;

FIG. 26 is a left side elevational view of the foldable mat as shown in FIG. 23;

FIG. 27 is a top plan view of the foldable mat as shown in FIG. 23;

FIG. 28 is a bottom plan view of the foldable mat as shown in FIG. 23;

FIG. 29 is a perspective view of the foldable mat of FIG. 23 in a folded orientation;

FIG. 30 is a front elevational view of the foldable mat as shown in FIG. 29;

FIG. 31 is a right side elevational view of the foldable mat as shown in FIG. 29;

FIG. 32 is a left side elevational view of the foldable mat as shown in FIG. 29;

FIG. 33 is a top plan view of the foldable mat as shown in FIG. 29; and,

FIG. 34 is a bottom plan view of the foldable mat as shown in FIG. 29.

The dotted lines represent the claimed fold lines of the foldable mat. The evenly spaced broken lines representing the handles are unclaimed portions of the foldable mat.
